UNITED STATES PATENT OFFICE.

SAMUEL V. REEVES, OF HADDONFIELD, NEW JERSEY.

COMBINATION HOT-WATER STOVE.

Application filed April 26, 1922. Serial No. 556,722.

To all whom it may concern:

Be it known that I, SAMUEL V. REEVES, a citizen of the United States, residing at Haddonfield, county of Camden, State of New Jersey, have invented a new and useful Combination Hot-Water Stove, of which the following is a specification.

My present invention comprehends a novel construction and arrangement of a combination stove wherein a plurality of fire pots are employed so that the stove can be employed the entire year provision being made whereby one of the jackets can be replaced or rendered inoperative to provide hot water. In this manner the stove can be used not only to heat a radiating system but also to heat water for bath and kitchen purposes and in the summer time the radiating system can be rendered inoperative and the amount of fire employed correspondingly reduced.

It further comprehends a novel hot water stove wherein a single base with a single or divided ash pit and with a single exit pipe to a chimney can be employed in conjunction with a plurality of water circulating heaters, the arrangement being such that both fires can be operated simultaneously or singly as may be desired, suitable dampers being employed to provide for a single or joint control of the two separated fires.

It further comprehends a novel stove having a plurality of separate water circulating heaters having a plurality of fires which can be operated as one fire or as a united fire provision being made for changing from one system to the other.

It further comprehends a novel construction of a combination stove having a plurality of water heating jackets either or both of which can be replaced with a solid cast iron heating and cooking fire pot and wherein one or both of said fire pots may contain a water circulating back or block or water circulating heating rings may be used above or below these heating and cooking fire pots as may be desired.

It further comprehends a novel combination stove of the character hereinbefore set forth wherein an ash ring may be employed below the water heating jacket or cooking and heating fire pot.

It further comprehends a novel combination stove wherein a water heating jacket is provided in conjunction with a water

back and provision is made whereby the water heating jacket or water back can be insulated so that only the water back or jacket will be affected by the heat.

60

Other novel features of construction and advantage will hereinafter more fully appear in the detailed description.

For the purpose of illustrating my invention, I have shown in the accompanying drawings embodiments thereof which are at present preferred by me, since these embodiments will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents, in front elevation, a combination stove, embodying my invention.

Figure 2 represents a top plan view of Figure 1.

Figure 3 represents a section on line 3—3 of Figure 2.

Figure 4 represents a top plan view of the stove with the top plate removed.

85

Figure 5 represents a section on line 5—5 of Figure 2.

Similar numerals of reference indicate corresponding parts.

Referring to the drawings.

90

Referring first to Figures 1 to 5 inclusive, 1 designates the base or foundation on which is seated the base top 2 which is provided with the doors 3 having the slide dampers 4 therein. The base top 2 carries at its upper portion sets of grates 5 and if desired separate ash chambers 6 and 7 can be formed by inserting a plate 8, see Figure 3, so that the draft for primary combustion to each stove unit may be independently controlled if desired by means of its respective damper 4. The ash pit ring 2 is recessed to receive the water-jackets 9 which form the fire pots and these water jackets are cored out to form a water chamber 10 with which communicate the cold water pipe inlet 11 and the hot water outlet pipe 12.

100

The juxtaposed walls of the two water jackets are connected by a flanged thimble 13 and are provided with registering apertures 14 to receive such thimble so that the

110

two fire pots act as a single fire pot or they can be made independent by inserting the fire bricks 15 which fit the apertures 14 and are secured in place by means of the clamping plates 16 and the fastening device 17 such as, for example, a bolt and nut, which passes through the clamping plates and the fire bricks and overhang the inner walls of the fire pot.

10 18 designates the top casing which forms the chambers 19 and is provided with a partition 20 having an opening 21 which may be opened or closed by means of the slide damper 22. 23 designates the exit 15 opening which communicates with the smoke pipe 24 and the communication between this flue opening 23 and the chamber 19 is controlled by means of the slide dampers 25 and 26 so that each fire pot if desired 20 may be operated as an independent stove unit or as a combined stove as may be desired in accordance with conditions and requirements met with in practice. The top of the stove is provided with the removable 25 lids 27 so that the top of the stove can be used for cooking, ironing and other domestic purposes. The upper plate 28 which is carried by the top rings 18 is provided with a slot 29 through which an extension of the 30 damper 22 extends to form a projecting portion which can be manually actuated.

In a similar manner a slot 30 is provided for the slide damper 25 and a slot 31 is provided for the slide damper 26. The 35 chamber of the water jacket 10 is constructed in accordance with my prior Patent #1,156,929, dated Oct. 15, 1915, or my prior Patent #1,190,460, which affords one-hundred per cent fire contact, it being seen that 40 the water chamber has its greatest diameter at the point at which the greatest heat is generated.

Having thus described my invention, what I claim as new and desire to secure by Letters Patent, is:—

45 1. A combination hot water stove having a single base unit, a single, independent base top unit mounted thereon, a pair of independent grates, a pair of individual, cored 50 fire pot units mounted upon said base top,

there being a separate grate for each unit, a water chamber surrounding each fire pot, a bolt and nut for securing said fire pot units together as a single unit, a top member constituting an independent unit having a chamber communicating with said fire pots all of said units being separably fitted together in superimposed relation, a single discharge flue, and independent dampers for controlling the exit of products of combustion from said fire pots to said discharge flue. 55

2. A combination hot water stove having a single base unit, a single, independent base top unit mounted thereon, a pair of independent grates, a pair of individual, cored fire pot units mounted upon said base top, there being a separate grate for each unit, a water chamber surrounding each fire pot, means including a bolt and nut for interchangeably subdividing said fire pots into two chambers, a top member constituting an independent unit having a chamber communicating with said fire pot all of said units being separably fitted together in superimposed relation, a single discharge flue, and independent dampers for controlling the exit of products of combustion from said fire pots to said discharge flue. 70

3. A combination hot water stove having a single base unit, a single, independent base top unit mounted thereon, means for interchangeably subdividing said base top unit into two separate compartments, a pair of independent grates, a pair of individual, cored fire pot units mounted upon said base top, there being a separate grate for each unit, a water chamber surrounding each fire pot, a bolt and nut for securing said fire pot units together as a single unit, a top member constituting an independent unit having a chamber communicating with said fire pots all of said units being separably fitted together in superimposed relation, a single discharge flue, and independent dampers for controlling the exit of products of combustion from said fire pots to said discharge flue. 80

SAMUEL V. REEVES.
